SEALING MACHINE AND THE LIKE

Leon E. La Bombard, Nashua, N. H., assignor to
 The International Paper Box Machine Company, Nashua, N. H., a corporation of New Hampshire

Application September 16, 1942, Serial No. 457,827

17 Claims. (Cl. 154—42)

This invention relates to mechanism for selectively operating upon a single article or a group of articles being moved along a guideway, and the object thereof is to provide means for temporarily arresting the articles to cause them to dwell with means for performing an operation upon the articles during said dwell.

A further object of the invention is to provide mechanism of the character described with two guideways with means for alternately feeding an article or a group of articles to the respective guideways, alternately causing the articles in one guideway to dwell during the movement of the articles along the other guideway with means for performing an operation on the article or group of articles which is stationary during said dwell.

Another object of the invention is to provide novel means for selectively feeding an article or a group of articles to the guideway or guideways.

More specifically, the invention relates to machines for sealing envelopes or bags of thermoplastic material or having edge portions of thermoplastic material by use of heating bars, and the invention is illustrated and described herein as embodied in mechanism for sealing the contiguous edges of folded sheets of thermoplastic material or folded sheets having superimposed contiguous edge portions provided with thermoplastic adhesive material. The sheets from which the envelopes or bags are made are so folded that edge portions of the material overlap each other. When heat is applied to any of the overlapped portions, a seal is effected, therefore bags of various shapes and sizes can be made.

It is customary to effect such sealing by heated rollers, but it is found that rotary sealing is not as dependable as sealing by flat heated bars of varied designs where the heat and dwell can be better regulated for best results as the sealing materials are critical to pressure and dwell of the heating means as well as the shape and pattern of the seals. This has heretofore been accomplished mainly by manual operation necessarily of slow process.

It is found that the best results are obtained by utilizing heated bars where the heat is controlled to a plus or minus one degree. These bars are made to close upon the material and allowed to remain or dwell for one second or more. An equal length of time is allowed to open the jaws and again close them.

In mechanisms heretofore employed it is possible to seal as many as thirty large bags per minute, which are, for example, 36-72 in. in

length, a greater percentage of the bags however are from nine to fifteen inches in length.

By reason of the present invention, means are provided for feeding into the jaws of the heated bars while open, a plurality of bags to form a group of two to four as illustrated herein, and a machine may be selectively operated to feed single bags or groups of two, three, or more, and the sealing of each group accomplished in the same time as that required for the sealing of a single long bag. This obviously results in greater production, conservation of heat, more uniform heating regulations of the bar, as the heat is dissipated uniformly throughout its length.

These and other objects and features of the invention will more fully appear in the following description and the accompanying drawings, and will be particularly pointed out in the claims.

A preferred embodiment of the invention is illustrated in the drawings as a machine for sealing together the side edges of a sheet of thermoplastic material which has been previously folded transversely midway of its length thereby to form an envelope, bag, or container which will be waterproof and will therefore serve as a container for liquid, semi-liquid, or other materials, and which if the open end of the bag is similarly sealed, will effectively be impervious to the admission of air or moisture vapor, and will therefore preserve the contents of the bag indefinitely.

Preferred embodiments of the invention are illustrated in the accompanying drawings, in which,

Fig. 1 is a side view partially in elevation, and partially in section of a front-end portion of a sealing machine embodying the invention;

Fig. 2 is an enlarged detail sectional view showing a recess in the feeding cylinder and frictional article engaging means detachably mounted therein;

Fig. 3 is a similar view illustrating a block or blank that is substituted for the frictional member where a feeding of a blank during the rotation of the feeding cylinder is not desired;

Fig. 4 is a view similar to Fig. 1 illustrating the rear-end portion of the machine and is a continuation of Fig. 1;

Fig. 5 is a detail view of a portion of the feeding cylinder and the front-end portion of sealing mechanism where a single guideway for the articles to be sealed is employed;

Fig. 6 is a plan view of a bag or envelope liner folded within a box blank, a portion of the box blank being illustrated in dotted lines in extended position;

Fig. 7 is an enlarged transverse sectional view of the upper and lower guideway for the articles to be sealed, mechanism for moving the articles along the respective guideways, the cooperating heated sealing bars showing them in position to seal articles in one of the guideways while the other guideway is open to receive an article or a group of articles;

Fig. 8 is an enlarged detail view showing the upper and lower guideways and the mechanism for alternately clamping the articles to be sealed on one of the guideways with rollers for simultaneously pressing the articles upon the track of the other guideway;

Fig. 9 is a plan view of the construction illustrated in Fig. 8, and

Fig. 10 is a transverse sectional view showing the upper and lower side of a box or carton with the thermoplastic sealing envelope therebetween, and illustrating portions of the carton forming the side of the box bent downwardly to expose the edges of the envelope for heat sealing.

The machine illustrated herein comprises parallel side frames 1, having at their front and rear ends respectively, legs 2 and 3 which rest on the floor (Figs. 1 and 4) and are connected by suitable front tie rods including a tie rod 4, other tie rods 5, 6, and 7, near the front end, and tie rods 8, 9, and 10 near the rear end (Fig. 4). The side frames are also provided with upward extensions intermediate of the tie rods 5, 6, 7, and the front end of the machine which are connected by an arch 11 preferably in the form of a channel bar upon which is mounted a suitable hopper for supporting a stack of blanks or other articles to be operated upon as will hereinafter more fully appear.

The machine comprises a guideway or preferably two guideways which extend longitudinally of the machine with means for successively feeding single articles, or a predetermined number of articles to form a group, to said guideway or alternately to each of said guideways, means for moving the articles along the guideway, and means for arresting the single article or a group of articles in predetermined positions to permit an operation to be performed upon an article or group of articles during the dwell thereof. The guideways are formed by parallel pairs of upper and lower track members and an intermediate pair of track members. The lower track members as shown herein comprise lower parallel bars 12 which are mounted near their ends fixedly upon the tie rods 8 and 9. The upper track members are in the form of similar parallel bars mounted near their ends upon the tie rods 5 and 6, and the intermediate track members comprise relatively narrower parallel bars 14 which are mounted adjacent their ends upon cross girders 15 and 16 which are mounted in the side frames 1.

Suitable means are provided for moving the article or articles lengthwise of the guideways. As illustrated herein such means comprises a lower endless belt 17 which is mounted upon pulleys 18 and 19 which are respectively mounted upon a shaft 20 journaled in the front end of the track members 12, and upon a shaft 22 at the rear end of the track members which is journaled at its ends in the side frames 1. The upper run of the belt 17 extends in parallelism with and is substantially flush with the upper walls of the lower track members 12. A similar endless belt 23 is mounted at its front end upon a pulley 24, the shaft 25 of which is journaled in

the front end of the upper track members 13 and at its rear end upon a pulley 26 which is mounted upon a shaft 27 which is journaled in the rear ends of the side frames 1. The lower run of the endless belt 23 is flush with the lower walls of the track members 13. Suitable spacing and belt-supporting plates 28 and 29 are interposed respectively between the track members 12 and between the track members 13 and are connected to the respective track members by oppositely extending screws 30 which are mounted in vertical slots near the edges of the track members and are provided with shouldered heads of greater diameter than the width of the slots thereby enabling the belt-supporting plates to be adjustably positioned properly to support the adjacent runs of the endless belts 17 and 23 throughout their lengths and to cause the belts properly to engage and move the articles along the guideways.

Desirably means are also provided for pressing the articles against the respective endless belts to insure proper forwarding of the articles. In the construction illustrated herein such means comprises a series of suitably spaced rollers 31 which are mounted in the forked ends of levers 32 which are fulcrumed upon shafts 33, the ends of which are journaled in the intermediate parallel track members 14. The opposite ends of the levers 32 are connected to flexible leaf springs 34, the forward ends of which are secured in shafts 35 which are movable upwardly and downwardly in suitable preferably circular recesses 36 in the track members 14. Means operable by the movement of the clamping members, as will herein-after be described, raise and lower the shafts 35 in such manner that the rollers 31 will alternately clamp the articles against the traveling belts 17 and 23 as they are carried along the respective guideways by the belts, thereby maintaining the proper spacing and registry of the articles.

Means are provided for arresting a single article or group of articles temporarily in predetermined positions in order that operations may be performed upon the said articles during the dwell thereof.

As illustrated herein, means are provided for alternately clamping the article or groups of articles in the lower guideway upon the lower track members 12 and for clamping the articles in the upper guideway upon the upper track members 13. This mechanism comprises parallel bars 37 preferably of a width equal to that of the track members 14 which are suitably mounted upon and extend lengthwise of the track bars 14 and slidably engage the sides thereof. The clamping bars 37 are provided with upwardly and rearwardly inclined slots 38 and 39 located respectively adjacent the front and rear ends of the clamping bars 37. A shaft 40, which is mounted in the intermediate track members 14, extends into the rear slots 39, and a shaft 41, which is rotatably mounted in the side frames 1 and extends through the front end portion of the intermediate track members 14, extends through the slots 38 in the forward ends of the clamping bars 37.

The shaft 41 is provided with fins or teeth 42, having rounded end portions which engage complementary recesses in the upper walls of the slots 38 (see Fig. 8), so that when the shaft 41 is rotated in a clockwise direction, the fins 42 will raise the forward end of the clamping bars 37 and by reason of the inclination of the slot 38 will move the clamping bars rearwardly. At the same time the inclined slots 39 at the rear

ends of the clamping members 37 will similarly raise the rear ends of the clamping bars an equal distance, thereby causing the clamping bars to clamp the articles in the upper guideway firmly against the upper track bars 13, and arrest the movement of the articles while the upper belt continues its movement. During the dwell of the articles thus clamped against the upper track bars another article or group of articles will be forwarded along the lower guideway, while an operation is performed upon those which dwell in the upper guideway.

When the shaft 41 is rotated in the opposite or counterclockwise direction, articles in the lower guideway will be similarly clamped by the clamping bars 37 upon the lower track bars 12, and caused to dwell to enable an operation or operations to be performed upon them, as shown in Fig. 7.

The clamping bars 37 are provided with a series of horizontal slots 43 into which extend the ends of the shafts 38 for actuating the levers 32 having the presser rolls 31.

As the clamping bars 37 are moved downwardly and forwardly by the counterclockwise rotation of the shaft 41, the shafts 38 (which are connected by leaf springs 34 to the forward ends of the levers 32), are moved downwardly thereby raising the rollers 31, into yielding engagement with the articles upon the upper guideway thus clamping them against the lower run of the upper conveyer 23, as illustrated in Fig. 8. This movement of the clamping bars 37 serves to clamp the articles traveling in the lower guideway against the track members 12 of the lower guideways, and arrest them so that operations may be performed upon them during the dwell. Obviously the reverse action takes place when the shaft 41 is rotated in a clockwise direction to clamp the articles against the upper track members 13. By reason of this construction, the article or group of articles in one guideway is caused to dwell while another article or group of articles is being forwarded to a predetermined position or predetermined positions in the other guideway.

Any suitable mechanism may be provided for performing an operation or operations upon the articles or group of articles in the respective guideways during the dwell thereof. The preferred embodiment of the invention is illustrated herein as adapted to seal contiguous sides of sheets of thermoplastic material, or sheets having edge portions of thermoplastic material adapted to be sealed together by the application of heat and pressure, the sheets being folded midway of their length so that when the side edges are thus sealed together, a waterproof bag or envelope is produced. Such an envelope may be used alone or may form the lining of a box which when filled with liquid, semi-solid, or solid material, and the open end when similarly sealed will form a hermetically-sealed container.

The means for sealing together the overlapping contiguous side edges as illustrated herein comprises heated upper and lower pairs of bars which extend longitudinally in parallelism to the upper and lower track members respectively and an intermediate heated bar which extends in parallelism with the intermediate track members with mechanism for raising and lowering the intermediate heated bar to cause it alternately to clamp and heat-seal the side edges of the articles during the dwell thereof in one guideway, while an article or group of articles is be-

ing moved to sealing positions in the other guideway.

The heat-sealing mechanism illustrated in the accompanying drawings comprises supplemental side frames 44 which are slideably mounted adjacent their front ends upon the tie rods 1, and at their rear ends upon the tie rod 10. The side frames 44 are provided at their upper edges with similar inwardly extending horizontal flanges 45, and suitable metallic heating members 46, which are secured to the underside of the inner ends of the respective horizontal flanges 45, present horizontal faces which are flush with the under faces of the tracks 13 of the upper guideway.

Any suitable means may be provided for supplying heat to the respective heating members, such as electric heating units 47 within and extending longitudinally thereof.

The supplemental frames 44 are also provided with lower inwardly extending flanges 48 having mounted upon the upper surfaces of their inner ends similar heating members 49, the upper surfaces of which are flush with the upper surfaces of the lower track members 12.

Intermediate heating members 50 cooperate alternately with the upper and lower heating members 46 and 49 to heat-seal the edge seams of articles carried respectively by the upper and lower guideways. As illustrated herein, the intermediate heating members 50 are provided at their front and rear ends with dovetail extensions which are seated in complementary slots in the bifurcated ends of arms 51 and are clamped therein by screws 52. The arms 51 which are thus secured to or adjacent to the front and rear ends of each intermediate heating member 50, are provided at their opposite ends with vertical apertures to receive vertical actuating bars 53, which are mounted in suitable bushings 54 and 55 in the flanges 45 and 48 respectively. The arms 51 are fixedly but adjustably secured to the actuating bars 53 by set screws 56.

Spiral springs 57 which are interposed between the upper sides of each of the arms 51 and the upper horizontal flanges 45 of the side frames serve normally to force the arms 51 downwardly so that the intermediate heating members 50 will cooperate with the complementary lower heating bar 49 to heat-seam the contiguous edges of the articles dwelling in the lower guideway.

Suitable means are provided for raising the actuating bars 53 to cause the intermediate heating members 50 to cooperate with the upper heating bars 46 to heat-seal the articles when dwelling in the upper guideway. As illustrated herein the lower ends 59 of the actuating bars 53 have secured to them follower rolls 58 which engage similar pairs of cams at the front and rear ends of the supplemental frame. The cams 59 having hubs 60 with reduced end portions which are journaled in the supplemental side frames 44 and are held in place by collars 62 which are secured by set screws to the hubs at the outside 65 of the frame 44. The hubs 60 of the cams at the front end of the machine are slideably mounted by feather and slot connections upon a shaft 63 adjacent the front end of the machine and the hubs 60 of similar cams are similarly mounted upon a shaft 64 adjacent the rear end of the machine, the shafts 63 and 64 being journaled in the main frames 1 of the machine.

Suitable means are provided for moving the side frames 44 toward and from each other properly to position the heat-seaming members with

respect to the edges of the articles of different widths which are to be seamed. This is accomplished in the embodiment of the invention, as illustrated in dotted lines in Fig. 4, by providing rods 65, the opposite end portions of which are reversely screw threaded to engage the complementary screw threads in the respective side frames. Suitable means are provided for simultaneously rotating both of the screw threaded rods 65, which as illustrated herein comprises sprockets 66 secured respectively to the rods 65 connected by an endless sprocket chain 67. A suitable crank (not shown) is provided for rotating one of the screw threaded rods 65. By reason of this construction the heat-seaming members may be positioned at any required distance from the guideways for the articles properly to engage any desired portion of the superimposed edges of the articles to be sealed.

It is believed to be obvious that by reason of the construction above described single long articles may be successively sealed or otherwise operated upon, or that a predetermined number of like articles forming a group may be simultaneously sealed or otherwise operated upon when successively fed into one of the guideways or alternatively into the upper and lower guideways.

An important feature of the invention consists in providing adjustable means for selectively feeding single articles or a predetermined number of shorter articles forming a group into the respective guideways. The feeding mechanism for accomplishing this purpose which is illustrated in the accompanying drawings comprises a magazine or hopper to receive a stack of blanks or other articles to be operated upon, and which is adjustable to receive stacks of articles of different lengths.

As illustrated herein, the hopper comprises a front section 68 which is mounted upon rods extending upwardly and forwardly from a suitable bracket 69 carried by the arch 11 at the front end portion of the machine. The front section 68 of the hopper has an open bottom to permit the front edge portion of the lowermost article in the stack to rest upon the periphery of a cylindrical feeding wheel 70. A gate 71 is interposed between the front hopper section 68 and the bracket 69 and is provided with a rearwardly extending flange 72 having mounted therein an adjusting screw 73 which engages a complementary screw threaded socket in the bracket 69. The screw 73 is provided with a milled head 74 by means of which the screw may be rotated readily to adjust the lower edge of the gate 71 accurately with respect to the periphery of the feed wheel 70 so that but a single blank or article will be removed from the hopper by suitable means upon the feed wheel adapted, preferably frictionally, to engage the under surface of the article.

The means for mounting the hopper upon the bracket 69, which is illustrated herein, comprises parallel rods 75 which are respectively seated in sockets 76 in flanges 77 extending laterally from the bracket 69 and the rear section 68 of the hopper is provided with laterally extending bosses 78 which are slidably mounted upon the rods 75. The front hopper section 79 is likewise provided with laterally extending bosses 80 which are slidably mounted upon the bars 75 and adapted to be held in adjusted positions thereto to support the front end of the stack of blanks or other articles to be operated upon. The front hopper 75

section 78 is provided with a front wall 81 which merges into a preferably downwardly inclined bottom wall 82 to support the front end of the stack of articles. Desirably the front wall 81 extends only a substantial portion of the height of the hopper and is provided with a forwardly curved section 83 to form a guide which will facilitate the introduction of the stack of articles to the hopper.

The rods 75 are of such length as to permit the front section 78 of the hopper to be adjusted outwardly (to the left) to the position illustrated in dotted lines to support articles of the greatest length which are adapted to be singly operated upon by the sealing mechanism or other means for operating upon the article. As shown herein, the front hopper section is illustrated in full lines in an intermediate position and is illustrated in dotted lines adjacent the rear section of the hopper in position to support a stack of short blanks, a predetermined number of which are to be fed to the sealing mechanism to form a group adapted simultaneously to be sealed or otherwise operated upon as heretofore described.

In order to feed successively single articles, or selectively to feed successively a plurality of shorter articles to form a group an adjustable cylinder is provided which as shown herein has suitably spaced detachable means for frictionally engaging the under surface of the lowermost article of the stack so that by employing a predetermined number of said frictional engaging means the cylinder may be adapted upon each revolution to forward into the guideway one article or a predetermined number of articles to form a group not exceeding in group length that of a single article. In the preferred construction illustrated the periphery of the feeding cylinder is provided with a plurality of suitably spaced similar longitudinal rectangular recesses 84 in which frictional members or non-frictional blocks having peripheral surfaces forming continuations of the surface of the cylinder may be seated.

One of the blocks containing frictional article-engaging members is illustrated in Fig. 2 and comprises a steel block 85 adapted to be seated in a recess 84 and fixedly secured therein by a screw 86. The block 85 is provided with a longitudinally extending recess having a cylindrically curved bottom 87 and an undercut forward wall 88. A sheet section of frictional material 89, such as rubber, which is adapted to be seated within the recess in the block 85 with its periphery coincident with the curvature of the cylinder, is provided with a forwardly extending tapering section which extends beneath the undercut wall 88 and is engaged by the ridge portion of a clamping plate 91 which is mounted upon guides pins 92 seated in the block 85 and is forced into clamping engagement with the tapered portion of the rubber block by a screw 93. The blocks containing frictional material may be selectively applied to such recess in the periphery of the cylinder as may be necessary to feed a predetermined number of articles upon each half revolution of the cylinder, the other recess of the cylinder being filled with similar blocks having a peripheral surface coincident with the surface of the cylinder but not presenting frictional surfaces. One of these non-frictional blocks, which may be thus substituted, is illustrated in Fig. 3 and comprises a preferably steel block 94 presenting a cylindrical surface forming a continuation of the cylindrical

periphery of the cylinder and secured in the socket 84 by the screws 86.

The construction illustrated in Fig. 1 shows blocks having frictional surfaces in three of the sockets symmetrically disposed on each half of the cylinder. Where articles of maximum length are to be fed the frictional blocks are mounted in diametrically opposite recesses herein indicated as *a*, so that a long article may be fed upon each half revolution of the cylinder.

Where articles half of the maximum length are to be fed in groups of two to the mechanism for acting upon the article intermediate blocks having frictional surfaces are placed in sockets indicated as *b*.

Where groups of three articles are to be fed upon each half revolution of the cylinder blocks having frictional surfaces are introduced into the sockets indicated as *c* and where articles one-fourth of the length of the maximum article are to be fed blocks having frictional material are introduced into the sockets indicated as *d* and it will be noted that in this arrangement one of the sockets is the same as that previously indicated as *b* for half length articles. In any case each of the sockets which are not to be provided with frictional feeding mechanism are filled with a non-frictional block 84. Obviously other suitably spaced sockets may be provided for feeding single articles or predetermined groups containing more than four articles as will be readily understood by those skilled in the art.

Suitable mechanism is provided for actuating the feeding mechanism, the mechanism for forwarding articles along the guideway, and for arresting them in proper position and for operating the sealing mechanism or other means for operating upon the articles in properly timed relation to the feeding mechanism.

In the construction illustrated the feed drum 70 is mounted upon a main shaft 95 which is journaled in the side frames 1 of the machine and is driven from any suitable source of power. The main shaft is provided with a sprocket 96 which drives an endless sprocket chain 97, the upper run of which passes over a sprocket 98 upon the shaft 63 at the front end portion of the machine, thence beneath the sprocket 99 on the shaft 64 near the rear end of the machine, thence upwardly over a sprocket 100 on the shaft 22 which drives the lower conveyer belt 17, and thence downwardly under an idle sprocket 101 returning therefrom to the driving sprocket wheel 96 on the main shaft. The shaft 22 is provided with a gear 102 which meshes with a similar gear 103 upon the shaft 27 upon which the pulley 26 of the upper conveyer belt 23 is mounted. The lower and upper conveyer belts 17 and 23 are consequently driven continuously at the same speed and are adapted respectively to forward single articles or articles forming groups along the upper and lower guideways where the single article or groups of articles are alternately caused to dwell and to be operated upon in the manner heretofore described.

The mechanism for guiding a single article or a series of articles to form a group alternately to the lower and upper guideways upon each half revolution of the feeding cylinder comprises a switch 104 which is fixedly mounted upon a shaft 105 which is journaled in the front end of the intermediate track members 14. The shaft 105 has fixedly secured to it an arm 106 which is pivotally connected to a forked head 107 of a pitman 108 the lower end of which is connected

10 to a fork 109 which embraces a cylindrical collar 110 on the main shaft 95. The forked member 108 is provided with a follower roller 111 which engages a cam 112 which is fixedly secured to the shaft 95 and is so constructed and positioned as to raise the arm 106 and swing the switch 104 upwardly to direct the articles along the lower guideway, as illustrated in Fig. 1, during one-half revolution of the feeding cylinder 10 and to swing the switch 104 downwardly to guide the article or group of articles along the upper guideway during the other half revolution of the cylinder 10. Desirably a horizontal guide plate is interposed between the periphery of the cylinder and the leading end of the upper run of the conveyer belt 17 to insure proper delivery of the articles upon said upper run when the switch 104 is swung upwardly to guide the articles along the lower guideway, the switch 104 being sufficient to guide the articles in the upper guideway when swung downwardly.

When a single articles or group of articles have been fed to a predetermined position along one of the guideways the clamping members 31 are actuated to clamp the article or group of articles upon a guideway to permit an operation to be performed upon them while articles are being fed along the other guideway. As illustrated in Fig. 1 the mechanisms are in the position in which a group of articles has been properly positioned upon the lower guideway and the clamping members forced downwardly to clamp them against the lower track members 12. It has heretofore been pointed out that the clamping movements of the clamping members 31 are produced by the rotation of the shaft 41 with its fins 42 in the slots 38 of the members 31, as shown in Fig. 8.

The mechanism for oscillating the shaft 41 comprises an arm 113 which is fixedly secured to the shaft 41 and is pivotally connected at its end to the upper end of a pitman 114, the lower end of which is provided with a fork 115 which embraces a sleeve 116 upon the shaft 63. The fork 115 is provided with a follower roll 117 which engages a cam 118 which is fixedly secured to the shaft 63 and is so constructed and positioned as to raise the pitman 114 and cause the arm 113 to rotate the shaft 41 in a counterclockwise direction, thereby to move the clamping bars 31 forwardly and downwardly and thereby clamp the articles in the lower guideway upon the lower track members 12 during approximately one-half revolution of the shaft 63. The cam is so constructed that during the other half revolution it will move the clamping bars 31 longitudinally rearwardly and simultaneously raise the same to clamp the articles in the upper guideway against the lower faces of the track members 13, as heretofore described.

By reason of this construction the articles in one guideway will be caused to dwell for the performance of an operation upon the articles while another article or group of articles is being fed into a predetermined position or positions in the other guideway.

The means for sealing the articles while thus being caused to dwell in the lower guideway, which is illustrated herein, comprises the cams 59 which are mounted respectively upon the shafts 63 at the front end of the machine and the shaft 64 at the rear end of the machine which engage the follower rolls 58 upon the lower ends of the actuating bars 53 for the intermediate heating members 50, the cams 59 being so constructed as to permit the heating bars 50 to be

forced downwardly by the springs 57 in clamping relation to the edge portions of the articles to be sealed, as illustrated in Fig. 7, or to be raised against the pressure of the springs 57 to cause the heating members 58 to clamp the articles against the upper heating members 46 to seal the edges of the articles in the upper guideway.

Where articles of a maximum length are to be operated upon and the hopper section 79 positioned near the outer ends of the supporting bars 75, as illustrated in dotted lines in Fig. 1, means desirably are provided for supporting the central portion of the stack to prevent sagging. A preferred form of mechanism which is illustrated herein comprises a roller 109 which is mounted upon the forked head of a rod 120 which is adjustably clamped in a split bracket 121 mounted upon the tie rod 4 at the front end of the machine. The split bracket 121 is provided with ears which are engaged by a clamping screw having a handle 122 by means of which it can be actuated to clamp the rod 120 in any adjusted position so that the roller 109 will properly support the central portion of the stack of articles intermediate of the front and rear hopper sections 79 and 68.

While the present invention is illustrated in the main figures of the drawings as comprising a construction having two guideways for the articles to be sealed or otherwise operated upon, it is obvious that the upper guideway including the track and the article forwarding means may be dispensed with and only a single guideway employed in which case the feeding mechanism may be driven at half speed or a feeding cylinder provided with frictional feeding blocks properly spaced throughout the circumference of the cylinder may be employed. Such a mechanism is illustrated in Fig. 5 in which only such parts as are essential are designated by the same numerals as are employed in the main figures of the drawings.

One of the principal objects of the invention is to provide means for sealing the superimposed contiguous edges of the box liners of thermoplastic material or having edge portions formed of thermoplastic material or provided with thermoplastic cement, the liners being previously pre-folded midway of their length and secured at one or both ends to the complementary portions of a box blank which is provided with suitable fold lines. A box blank provided with a liner of this character is illustrated in Fig. 6. The box blank illustrated herein comprises a rectangular body portion 123 having suitable longitudinal and transverse fold lines to provide means for forming side and end members of the box and a top portion 124 which is integrally connected to the bottom portion by a wall 125 having a central fold line 126 to permit the top to be collapsed upon the body portion. The top and bottom portions each have a rectangular central portion 127 of equal area. The top member is provided with a longitudinal fold line providing side flaps 128 and an end flap 129 for the end of the box. The body is provided with longitudinal fold lines corresponding to those at the top of the box with end recesses 130 and 131 to permit infolding of end tabs 132 and 133 which form continuations of the side members 134 of the sides of the box.

The box blank is provided with a lining of thin thermoplastic material such as a Cellophane or cellulose thermoplastic material which is folded midway of its length and preferably 75

adhesively secured to the end portion 125 which unites the top and body sections of the box and the superimposed edges desirably but not necessarily are provided with a narrow area of thermoplastic adhesive 135. The liner desirably is of greater width than the top of the box and the foldable side portions 128 thereof but of narrower width than the bottom of the box and its foldable sides so that when the box is forwarded longitudinally along a guideway of the machine the heated members 46 or 48 and intermediate heated member 50 may be positioned to engage only the side edge portions of the liner and the side portions of the body of the box blank which extend therebeneath.

When a box blank thus constructed or a group of box blanks thus constructed are arrested in the respective guideways by the clamping members and the heating members clamped upon the side edges the liners will be properly side-seamed throughout their lengths to provide a waterproof liner which can be filled with liquid, semi-liquid, or solid material. The open end portion may thereafter be similar heat-sealed to provide a hermetically sealed container and the box properly folded to form a rigid protective covering for the receptacle.

It is sometimes desirable to bend down the side portions of the body of the box in such manner as to expose the side edges only of the liner for sealing purposes. Suitable means such as a plow or deflector may be provided for deflecting downwardly or upwardly the sides or a portion of the sides of the box blank as the blank is introduced into and during its movement through the guideways into the position illustrated in Fig. 10, thereby to expose the superimposed contiguous edges of the liner which are to be sealed together.

By reason of the present invention, therefore, thermoplastic articles, or articles having thermoplastic adhesive along their contiguous side edges may be rapidly sealed while secured in proper position upon a box blank, the timing of the mechanisms of the machine being such as to provide the necessary dwell to insure proper sealing of the side seams and the speed of the machine is limited only by the necessary dwell to insure complete sealing of the side seams.

By reason of the fact that the present invention permits the use of two guideways instead of one, in which an article or group of articles is caused to dwell in one guideway and be sealed while a similar article or group of articles is being fed into the other guideway, the capacity of the machine is doubled over that in which a single seam-sealing operation is performed.

While the invention is particularly described herein as embodied in a machine for performing the operation of sealing side seams of liners of thermoplastic material or having side edge portions provided with thermoplastic adhesive material while attached to box blanks, it will be understood that other operations may be performed upon articles similarly fed singly or in groups and caused to dwell, such, for example, as operations performed by perforating mechanism, printing or stamping mechanism, string applying mechanism, etc.

It will therefore be understood that the particular embodiment or embodiments of the invention which are shown and described herein are of an illustrative character and not restrictive of the meaning and scope of the following claims.

Having thus described the invention, what is

claimed as new, and desired to be secured by Letters Patent, is:

1. A machine adjustable to operate upon a single long article or a group of aligned short articles in the same period of time comprising a guideway for the article or articles, means for successively feeding articles to the guideway, means for adjusting the feeding means to deliver a single article or a predetermined number of shorter articles to form a group not exceeding in group length the length of the long article, means for moving the articles along said guideway, means for causing the article or the group of articles to dwell, and means for performing an operation upon the single article or articles of the group during said dwell.

2. A machine adjustable to operate upon a single long article or a group of aligned short articles comprising a guideway, a continuously operating conveyor cooperating therewith to move the articles along the guideway, means for successively delivering the articles to the guideway, having adjustable means to deliver a long article or a predetermined number of shorter articles to form a group not exceeding in length that of the long article, means for temporarily arresting the article or the group of articles in predetermined position upon said guideway, and means for performing an operation upon each article while thus arrested.

3. A machine adjustable to operate upon a single long article or upon groups of aligned short articles comprising separate guideways for the articles, adjustable feeding means for selectively delivering to the respective guideways a long article or a predetermined number of shorter articles forming a group not exceeding in group length the length of the long article, means for alternately directing the articles or predetermined groups of articles to the respective guideways, means for moving the articles along the respective guideways, means for alternately, temporarily arresting the article or group of articles upon one of said guideways to cause a dwell thereof during the movement of the articles along the other guideway, and means for performing an operation upon the arrested article or group of articles during said dwell.

4. A machine adjustable to operate upon a single long article or a group of aligned short articles comprising a stationary track and a continuously operating conveyor cooperating therewith to move the article or articles along said track, adjustable means for selectively delivering single long articles or a predetermined number of short articles not exceeding in group length the length of the long article, means for temporarily clamping the article or group of articles in predetermined position upon said track during the same predetermined period of time, and means for performing an operation upon each article while thus arrested.

5. A machine adjustable to operate upon a single long article or a group of aligned short articles comprising a track and a continuously operating endless conveyor cooperating therewith to move the article or articles along said track, adjustable means for successively delivering to the track in the same period of time a long article or a group of short articles, means for temporarily clamping the article or group of articles upon the track in predetermined position as to cause the articles to dwell, and means for performing an operation upon each article during said dwell.

6. A machine adjustable to operate upon a single long article or group of aligned short articles

comprising a guideway having cooperating upper and lower pairs of stationary parallel track members to guide the articles therebetween, means for moving the articles along said tracks, adjustable means for successively delivering to said guideway, single long articles or alternatively for successively delivering to said guideway a plurality of suitably spaced shorter articles to form a group not exceeding in group length that of the long article, clamping means mounted upon one of said pairs of track members, and means for actuating the same to clamp the single article or the group of articles temporarily upon the other pair of track members to cause the articles to dwell, and means for performing an operation upon the article or articles during said dwell.

7. A machine adjustable to operate upon a single long article or a group of longitudinally spaced short articles comprising a guideway having cooperating main and complementary pairs of stationary parallel track members to guide the articles therebetween, adjustable feeding means selectively operable to deliver long articles successively to said guideway or alternatively to deliver to said guideway a plurality of suitably spaced short articles to form a group not exceeding in group length the length of the long article, a continuously moving endless carrier mounted on the pair of main track members to engage and move the articles along said track, clamping means mounted upon the complementary pair of said track members, and means for actuating the same to clamp the article or a group of articles temporarily upon the main pair of track members to cause the article or articles to dwell, and means for performing an operation upon each article during said dwell.

8. A machine adjustable to operate upon a single long article or a group of aligned short articles comprising upper and lower pairs of stationary main parallel track members, a pair of complementary stationary parallel track members between and spaced from the upper and lower pairs of main track members respectively to provide upper and lower guideways, adjustable feeding means selectively operable to deliver long articles successively to the respective guideways or alternatively to deliver to the respective guideways a plurality of suitably spaced short articles to form a group not exceeding in group length the length of the long article, means for moving successive articles along respective guideways, means for selectively directing single articles or groups of aligned articles alternately to the respective guideways, clamping means mounted on the complementary pair of track members, means for actuating said clamping means alternately to clamp the articles in the upper guideway or the lower guideway temporarily upon the upper or lower pairs of track members, to cause the articles to dwell, and means for performing an operation upon the article or group of articles in one guideway during said dwell therein while the article or groups of articles are being moved along the other guideway.

9. A machine adjustable to operate upon a single long article or a group of suitably spaced aligned articles comprising upper and lower pairs of stationary main parallel track members, a pair of complementary stationary parallel track members between and spaced from the upper and lower pairs of parallel main track members respectively to provide upper and lower guideways, adjustable feeding means selectively operable to deliver long articles successively to the respective

guideways or alternatively to deliver to the respective guideways a plurality of suitably spaced short articles to form a group not exceeding in group length the length of the long article, means for moving successive articles along the respective guideways, means for selectively directing single articles or groups of articles to the respective guideways, clamping bars mounted upon and movable forwardly and backwardly longitudinally of the complementary parallel track members, means for actuating said clamping bars, means for alternately raising and lowering the clamping bars during the longitudinal movement thereof to clamp the articles within one guideway upon the main track bars of said guideway and to cause the same to dwell, and means for performing an operation upon the article or group of articles during said dwell while articles or groups of articles are being moved along the other guideway.

10. A machine adjustable to operate upon a single long article or a group of aligned short articles comprising upper and lower pairs of stationary main parallel track members, a pair of complementary stationary parallel track members between and spaced from the upper and lower pairs of main track members respectively to provide guideways, means for moving successive articles along the respective guideways, adjustable feeding means selectively operable to deliver long articles successively to the respective guideways or alternatively to deliver to the respective guideways a plurality of suitably spaced short articles to form a group not exceeding in group length the length of the long article, clamping bars mounted upon and movable longitudinally of the complementary parallel track members, means for actuating said clamping bars, means for alternately raising and lowering the clamping bars during the longitudinal movement thereof to clamp the articles within a guideway upon the main track bars of said guideway and to cause the same to dwell, guide roller mechanism pivotally mounted upon and between the respective pairs of complementary track members, and means actuated by the means for raising and lowering movements of said clamping bars, which clamp the articles against one pair of main track bars, to cause the rollers to engage the articles moving along the other guideway and press them against the forwarding means thereof and means for performing an operation upon the article or group of articles during their dwell while the articles or groups of articles are being moved along the other guideway.

11. A machine adjustable to operate upon a single long article or a group of suitably spaced short aligned articles comprising upper and lower pairs of stationary main parallel track members, a pair of complementary stationary parallel track members between and spaced from the upper and lower pairs of main track members respectively to provide guideways, traveling endless article-forwarding belts mounted upon and between each pair of main track members, adjustable feeding means selectively operable to deliver long articles successively to the respective guideways or alternatively to deliver the respective guideways a plurality of suitably spaced short articles to form a group not exceeding in group length the length of the long article, clamping bars mounted upon and movable longitudinally of the complementary parallel track members, means for actuating said clamping bars, means for alternately rais-

ing and lowering the clamping bars during the longitudinal movement thereof to clamp the articles within one guideway upon the main track bars of said guideway and to cause the same to dwell, a series of guide roller mechanism pivotally mounted upon and between said complementary track members, and means actuated by the raising and lowering movements of said clamping bars, which clamp the articles against respective main track bars, to cause the rollers to engage the articles moving along the other guideway and press them against the forwarding belt thereof and means for performing an operation upon the article or group of articles during said dwell while the articles or groups of articles are being moved along the other guideway.

12. A machine for heat-seaming together the walls of receptacle blanks of, or having contiguous edge portions, embodying thermoplastic material which comprises a guideway for the blanks, means for moving the blanks along the guideway, feeding means and means for adjusting the same selectively to deliver to said guideway in the same period of time a long blank, or a predetermined number of aligned shorter blanks to form a group, means for temporarily arresting the blank or group of blanks to cause a predetermined dwell, and means for applying heat to the contiguous edge portions of said blanks, or group of blanks during said dwell.

13. A machine for heat-seaming together the walls of receptacle blanks of, or having contiguous edge portions embodying thermoplastic material, which comprises a guideway for the blanks, means for moving the blanks along the guideway, feeding means and means for adjusting the same selectively to deliver to said guideway in the same period of time a long blank, or a predetermined number of aligned shorter blanks to form a group, means for temporarily arresting the blanks, or group of blanks, to cause a predetermined dwell, relatively movable parallel heated bars extending in parallelism with said guideway spaced to receive the edge portion of the blanks therebetween, and means for causing said heated bars to clamp and thermally to unite the edge portions of the blanks together during said dwell.

14. A machine for heat-seaming together the walls of receptacle blanks of, or having contiguous edge portions embodying thermoplastic material which comprises upper and lower guideways for the blanks, means for moving the blanks along the respective guideways, feeding means and means for adjusting the same selectively to deliver alternately to the respective guideways a long blank, or a predetermined number of aligned shorter blanks to form a group, means for alternately arresting the blank, or group of blanks, in one of the respective guideways to cause a predetermined dwell while a blank or a group of blanks is being moved along the other guideway, main stationary heated bars extending in parallelism with the respective guideways, complementary vertically movable heating bars intermediate of said main heating bars, and means for alternately raising and lowering said complementary heated bars to clamp and thermally to unite the edge portions of the blanks together during the dwell of said blank or group of blanks, in the respective guideways.

15. A machine for heat-seaming together the walls of receptacle blanks of, or having contiguous edge portions embodying thermoplastic material which comprises upper and lower guideways for the blanks, means for moving the blanks

along the respective guideways, feeding means and means for adjusting the same selectively to deliver alternately to the respective guideways, a long blank, or a predetermined number of aligned shorter blanks to form a group, means for alternately arresting the blank or group of blanks in one of the respective guideways to cause a predetermined dwell while a blank or a group of blanks is being moved along the other guideway, main stationary heated bars extending in parallelism with the respective guideways, complementary vertically movable heating bars intermediate of said main heating bars, and means for raising and lowering said complementary heated bars to clamp and thermally to unite the edge portions of the blanks together during the dwell of said blank or group of blanks, and means for simultaneously adjusting said heating bars laterally toward or from said guideways.

16. The method of sealing the superimposed edge portions of a liner of thermoplastic material, or having edge portions provided with thermoplastic adhesive, which liner is applied to a box blank having portions underlying or overlying the edge portions of the liner, which comprises selectively moving in the same period of time along a track a long box blank or a predetermined number of aligned shorter box blanks with the liners applied thereto, temporarily arresting the same in said predetermined position to cause a dwell, deflecting during the feeding movement the portions of the box blank which underlie or overlie the superimposed edge portions of the liner to expose said edge portions, and clamping together the continuous edge portions of the blank or

10 group of blanks by cooperating heating means during said dwell.

15 17. A machine for heat-seaming together the walls of receptacle blanks of, or having contiguous longitudinal edge portions embodying thermoplastic material, comprising a magazine for a stack of blanks, a rotatable cylinder having a series of detachable blank-engaging members, one or more of which can be selectively employed to deliver from the stack a single blank or a series 20 of aligned shorter blanks to form a group, a guideway to receive the blank or blanks successively delivered, having upper and lower pairs of parallel track members of sufficient length to receive a long blank or a group of shorter blanks, continuously operable means for forwarding the blanks along said guideway, a pair of parallel clamping members, mounted on one of said pairs of track members and means for moving the same into clamping engagement with the other pair of track members to cause the blank or group of blanks to dwell, parallel pairs of heating bars suitably spaced from opposite sides of and parallel with said track members, means for moving one of 25 said heating bars relatively to the other during the dwell of said blank or group of blanks to engage and heat-seam the edge portions thereof, and means for synchronizing the movements of said clamping members and heat-seaming members to the revolutions of said cylinder, whereby a group of blanks can be heat-seamed in the same period of time as that required for heat-seaming a single blank.

along the respective guideways, feeding means and means for adjusting the same selectively to deliver alternately to the respective guideways, a long blank, or a predetermined number of aligned shorter blanks to form a group, means for alternately arresting the blank or group of blanks in one of the respective guideways to cause a predetermined dwell while a blank or a group of blanks is being moved along the other guideway, main stationary heated bars extending in parallelism with the respective guideways, complementary vertically movable heating bars intermediate of said main heating bars, and means for raising and lowering said complementary heated bars to clamp and thermally to unite the edge portions of the blanks together during the dwell of said blank or group of blanks, and means for simultaneously adjusting said heating bars laterally toward or from said guideways.

16. The method of sealing the superimposed edge portions of a liner of thermoplastic material, or having edge portions provided with thermoplastic adhesive, which liner is applied to a box blank having portions underlying or overlying the edge portions of the liner, which comprises selectively moving in the same period of time along a track a long box blank or a predetermined number of aligned shorter box blanks with the liners applied thereto, temporarily arresting the same in said predetermined position to cause a dwell, deflecting during the feeding movement the portions of the box blank which underlie or overlie the superimposed edge portions of the liner to expose said edge portions, and clamping together the continuous edge portions of the blank or

10 group of blanks by cooperating heating means during said dwell.

15 17. A machine for heat-seaming together the walls of receptacle blanks of, or having contiguous longitudinal edge portions embodying thermoplastic material, comprising a magazine for a stack of blanks, a rotatable cylinder having a series of detachable blank-engaging members, one or more of which can be selectively employed to deliver from the stack a single blank or a series 20 of aligned shorter blanks to form a group, a guideway to receive the blank or blanks successively delivered, having upper and lower pairs of parallel track members of sufficient length to receive a long blank or a group of shorter blanks, continuously operable means for forwarding the blanks along said guideway, a pair of parallel clamping members, mounted on one of said pairs of track members and means for moving the same into clamping engagement with the other pair of track members to cause the blank or group of blanks to dwell, parallel pairs of heating bars suitably spaced from opposite sides of and parallel with said track members, means for moving one of 25 said heating bars relatively to the other during the dwell of said blank or group of blanks to engage and heat-seam the edge portions thereof, and means for synchronizing the movements of said clamping members and heat-seaming members to the revolutions of said cylinder, whereby a group of blanks can be heat-seamed in the same period of time as that required for heat-seaming a single blank.
